UNITED STATES PATENT OFFICE.

JOHN KIEWICZ, OF BOSTON, MASSACHUSETTS, ASSIGNOR TO THE REECE BUTTONHOLE MACHINE COMPANY, OF BOSTON, MASSACHUSETTS, A CORPORATION OF MAINE.

BUTTONHOLE-SEWING MACHINE.

Application filed August 31, 1927. Serial No. 216,612.

This invention relates to buttonhole sewing machines, and particularly to the cutter for cutting the buttonhole slit.

In those buttonhole sewing machines which are designed to sew a buttonhole with an eye, the cutter is formed with a straight cutting edge which terminates at one end in a more or less circular portion adapted to cut the eye of the buttonhole. In thus cutting the eye, this eye-forming portion of the cutter cuts or dies out from the cloth a small piece. The buttonhole cutter is usually made with a delivery passage extending from the eye-forming portion of the cutter and through which the pieces of cloth are delivered as they are cut out.

It sometimes happens, however, that when the cutter is raised after cutting a buttonhole, the small piece or fragment of cloth which has been cut out in forming the eye, will not be retained in the passage of the cutter, but may remain in place in the cloth from which it was cut. If this occurs, such piece or fragment of cloth is likely to be sewed into the buttonhole, thus forming an imperfect product.

It is one of the objects of my present invention to provide means for positively removing the pieces or fragments of cloth as they are cut, so as to obviate the possibility of such pieces becoming sewed into the buttonhole.

I attain this object by providing an ejector member, which is actuated at the proper time to force positively each piece or fragment of cloth into or through the delivery passage.

In order to give an understanding of my invention, I have illustrated in the drawings a selected embodiment thereof which will now be described, after which the novel features will be pointed out in the appended claims.

In the drawings, Fig. 1 is a fragmentary sectional view of a portion of a buttonhole sewing machine embodying my invention and showing the cutter raised.

Fig. 2 is a similar view showing the cutter in cutting position and illustrating the action of the ejector member.

Fig. 3 is a sectional view on the line 3-3 Fig. 1 showing the cutter block in plan view.

Fig. 4 is an underneath view of the cutter blade.

Fig. 5 illustrates the character of button-hole silt which is formed by the cutter.

Fig. 6 is a section on the line 6-6 Fig. 2.

Fig. 7 is a fragmentary perspective view of the upper end of the ejector member.

Inasmuch as the present invention relates simple to the buttonhole cutter of a button-hole sewing machine, I have not thought it necessary to illustrate the complete machine herein, but have shown only such part of a buttonhole sewing machine as is necessary to enable my invention to be understood.

In the drawings 1 indicates portions of the frame of a buttonhole sewing machine which carries the stitch-forming mechanism, the latter, however, not being shown herein. The machine illustrated is of that type in which the portion of the stitch-forming mechanism which controls the under thread is carried by a turret, indicated generally at 2 that is rotatable in bearings 3 carried by the frame 1, said turret having mounted thereon the usual throat plate 4, which is provided with a sewing opening through which the upper needle operates. The turret is given a half rotation at the eye end of the buttonhole for the purpose of carrying the stitching around the eye, as will be understood by those skilled in the art. The rotation of the turret is secured in usual way from a vertical shaft 44 carried by the frame 1 and which is geared to a pinion 5 on the turret as usual in buttonhole sewing machines.

The buttonhole cutter, which is of usual construction, is shown at 6 and it is carried by a cutter arm 7 pivoted to the frame at 8. Co-operating with the cutter 6 is the usual cutter block 9 which is situated beneath the cloth or work 10 and which supports the latter when the cutter is making its cutting stroke. This cutter block 9 is carried by the usual support or bracket 11.

The cutter herein shown is of the type usually employed for cutting a buttonhole slit with an eye at one end, said cutter having the straight cutting edge 12 which terminates at one end in a loop portion 13, which is more or less circular. This cutter will cut a buttonhole slit, such as shown in Fig. 5, said slit having the straight portion 14 which is cut by the cutting edge 12 and the eye 15 at one end which is cut by the eye-forming, portion 13 of the cutter. Said

cutter is also provided with the usual delivery passage 16 which extends from the eye-forming portion 13 upwardly through the cutter and which communicates with another passage 17 formed in the arm 7. 18 indicates a receiving chute which is secured to the stem of the arm 7 and is adapted to receive the cuttings as they are delivered from the passage 17. Each time 10 that the cutter cuts a buttonhole slit in a piece of cloth or other material 10, the eye-forming portion 13 of the cutter will cut out a cloth fragment 19 which will be situated within the eye-forming portion 13 when 15 the cutter is in its lowered position.

In order to prevent this cutting or cloth fragment 19 from falling out of the passage 16 or from remaining in the cloth when the cutter is raised, I have provided herein 20 means which is operative while the cutter is in its lowered or cutting position, to positively force the cloth fragment upwardly into the passage 16 where it will be retained by friction until it is forced upwardly and 25 outwardly through the passages 16 and 17 by the accumulation of cuttings beneath it as repeated buttonhole slits are cut. Such means is illustrated in the form of an ejector member 20 which is carried by the cutter 30 block 9 and operates in an opening formed therein. This ejector member is normally in its lowered position below the top of the cutter block and means are provided whereby when the cutter is in its lowered or 35 cutting position and has cut the cloth fragment 19 from the cloth 10, said ejector member is raised, as shown in Fig. 6 thereby positively forcing the cloth fragment upwardly into the passage 16 where it will be 40 retained by friction.

Any suitable means for actuating the ejector member 20 may be employed. In the construction illustrated, said member is actuated by the rotation of the turret which 45 occurs while the buttonhole cutter is in its lowered position, the turning movement of the turret at this time being for the purpose of restoring the turret to its normal position preparatory to the beginning of the stitching 50 on the buttonhole. So far as the invention is concerned, however, the ejector member might be operated from any other moving part of the sewing machine which is operating at the time the cutter is in its lowered 55 or cutting position. Where the ejector member is actuated from the turret, I may employ an actuating lever 21 which is pivoted at 22 to the portion of the frame carrying the turret and which has a curved portion 23 that parallels for a distance the periphery of the turret. This lever also has a portion 24 extending alongside of the support 11 and an up-standing portion 25 also situated adjacent to the support 11. 60 At the upper end of the up-standing portion

25 is a laterally extending portion 26 which extends through an opening 27 formed in the support 11 and which is situated beneath the lower end of the ejector member 20, said ejector member being acted upon by a 70 spring 30 which normally holds it in its lowered position, as shown in Fig. 1.

The turret 2 is provided on its upper end with a cam portion 28 that is adapted to engage a roll or stud 29 extending from the 75 lever 23. This cam portion 28 is so positioned that it will engage the stud 29 during the rotative movement of the turret which occurs while the cutter is in its lowered or cutting position. The engagement of the 80 cam 28 with the stud 29 will swing the lever 21 upwardly about its pivot thereby causing the end 26 thereof to engage the ejector member 20 and force the latter upwardly, as shown in Fig. 2. This upward movement of 85 the ejector member will, in turn, force the cloth fragment 19 upwardly into the passage 16 where it will be held by friction until it is moved further upwardly in said passage 90 by the next cloth fragment which is forced 95 into the passage by the ejector member. As the cloth fragments 19 accumulate in the passage 16 they are gradually forced outwardly through the passage 17 and on to the chute 18. 95

My invention, therefore, provides for positively removing each cloth fragment from the cloth as it is cut and thereby preventing any possibility that the cloth fragment will remain in the cloth and be sewed into the 100 buttonhole.

The ejector member 20 is shown as having points 31 at its upper end. The advantage of this construction is that these points furnish a better grip on the cloth fragment and 105 tend to hold the fragment in a position parallel with the surface of the cutter block as said fragment is forced upwardly into the passage 16. This reduces the danger that the fragment will turn and slip off from the 110 end of the ejector as the latter is raised.

I claim:

1. In a buttonhole sewing machine, the combination with a cutting block, of a buttonhole cutter co-operating therewith to cut a buttonhole slit, said cutter having at one end an eye portion for cutting the eye of the buttonhole, and also having a delivery passage extending from said eye portion through which are delivered the cloth fragments cut out by said eye portion, an ejector normally situated within the confines of the block, and means operative while the cutter is closed against the block for positively moving the ejector relative to the 115 block thereby to force said cloth fragment into the passage. 120

2. In a buttonhole sewing machine, the combination with a cutting block, of a buttonhole cutter co-operating therewith to cut 125

a buttonhole slit, said cutter having an eye portion and a delivery passage extending therefrom, an ejector normally situated within the confines of said block, and means 5 for positively moving said ejector relative to the block thereby to force positively into and through said passage the cloth fragment cut out by the eye portion.

3. In a buttonhole sewing machine, the 10 combination with a cutting block, of a buttonhole cutter co-operating therewith to cut a buttonhole slit, said cutter having an eye portion and a delivery passage extending therefrom, an ejector member, and cam 15 means to move said member positively through the eye portion of the cutter and into said passage as each buttonhole is cut whereby each cloth fragment cut out by the eye portion of the cutter is forced positively 20 into said passage.

4. In a buttonhole sewing machine, the 25 combination with a cutting block, of a buttonhole cutter co-operating therewith to cut a buttonhole slit, said cutter having an eye portion and a delivery passage extending therefrom, an ejector member normally located entirely within the block in line with the eye portion of the cutter when the latter is closed against the block, and cam means 30 to project said member beyond said block and through the eye portion of the cutter thereby to force positively the cloth fragment which is cut out by the said eye portion 35 into said passage.

5. In the buttonhole sewing machine, 40 which is provided with a rotary turret on which is mounted the under thread mecha-

nism, the combination with a cutting block, of a buttonhole cutter co-operating therewith to cut a buttonhole slit, said cutter 40 having an eye portion which cuts from the cloth a cloth fragment, and also having a delivery passage, and turret operated means to force said fragment into said passage.

6. In a buttonhole sewing machine, which 45 is provided with a rotary turret carrying the under thread mechanism, the combination with a cutting block, of a buttonhole cutter co-operating therewith to cut a buttonhole slit, said cutter having an eye portion and a delivery passage extending from 50 said eye portion, an ejector member operating in said block to force into said passage the cloth fragment cut out by said eye portion and means to actuate said member by 55 the rotation of the turret.

7. In a buttonhole sewing machine having a cutting block, a buttonhole cutter co-operating therewith and provided with an eye-forming portion and a delivery passage 60 leading from said eye-forming portion, and an oscillatory shaft by which the stitch-forming mechanism is given a turning movement, the combination with said cutter, cutting block and shaft, of an ejector operating 65 through the block for forcing into said passage the cloth fragment cut out by the eye-forming portion of the cutter, and means to actuate said ejector by the turning movement of the shaft. 70

In testimony whereof, I have signed my name to this specification.

JOHN KIEWICZ.
